UNITED STATES PATENT OFFICE

2,542,989

ELECTROLYTIC CELL

Charles Carter, Liverpool, and John V. S. Glass, Frodsham, England, assignors to Imperial Chemical Industries Limited, a corporation of Great Britain

Application September 9, 1946, Serial No. 695,622
In Great Britain August 27, 1941

Section 1, Public Law 690, August 8, 1946
Patent expires August 27, 1961

9 Claims. (Cl. 204—225)

1

This invention relates to improvements in electrolytic cells and more particularly to cells having a liquid electrode, e. g., mercury or an amalgam.

Various types and forms of electrolytic cells are known for electrolyzing an aqueous electrolyte having as one electrode a heavy liquid such as a sheet of mercury which flows over a horizontal or slightly inclined surface, with a second electrode formed of plates or blocks of solid material, e. g., carbon or graphite, arranged a short distance above the liquid electrode with the under-surface substantially parallel to the surface of the liquid electrode. Such cells are referred to as electrolytic cells of the liquid electrode type.

An example of such a cell is one for the electrolysis of brine in which the cathode is a continuous sheet of mercury flowing over a slightly inclined plane surface forming the bottom of a trough-shaped vessel, and the anode is formed of a number of plates of graphite immersed in the brine and suspended by graphite rods from one or more lids forming the cover of the cell. As a result of the electrolysis the mercury becomes an amalgam continuously increasing in strength as electrolysis proceeds, so that only at the beginning of its path is the electrode the chemical element mercury. Therefore, the word mercury as used in this specification and its appended claims will be understood to cover the resulting amalgams as well as the pure metal unless the context requires the narrower meaning. In operation the under-surfaces of the graphite anode plates wear away and the electrical resistance of the cell thus increases so that it is essential to have means for adjusting the height of the electrodes to compensate for this wear.

A principal object of this invention is the provision of electrolytic cells of the liquid electrode type of new form and design. A further object is the provision of electrolytic cells of the subject type provided with means external of the cell for adjusting the solid electrode position while the cell is in operation. Another object is the provision of liquid-electrode, electrolytic cells which may be operated at super-atmospheric pressures. A still further object is the provision of such cells which operate at relatively low voltage and which make possible very close control upon the reactions taking place within the cell and the efficiency of the process. An additional object is the provision of such cells in which the inter-electrode gap

2

may be changed or varied without fluid escaping from the cell even when the cell is operated under super-atmospheric pressure. Another object is the provision of such cells which permit the electrolyte flow between the inter-electrode gap to be readily controlled both as to quantity and velocity. Other objects and the entire scope of applicability of this invention will become apparent from the detailed description given hereinafter.

These objects are accomplished according to the present invention by providing in an electrolytic cell of the liquid electrode type comprising a lower part or base adapted to carry a liquid electrode denser than the electrolyte and an upper part or cover carrying solid electrodes disposed with their under-surfaces a short distance above the upper surface of the liquid electrode and substantially parallel thereto, means external of the cell for adjusting the height of the solid electrodes relative to the surface of the liquid electrode, and means for sealing the upper part of the cell to the lower part of the cell in a manner allowing movement of the one part relative to the other.

Advantageously, the external adjusting means comprises a plurality of screw threaded supports adapted on rotation to cause a vertical movement of the upper part of the cell relative to the lower part.

According to a further feature of the invention a particularly advantageous sealing means comprises a resilient deformable packing located beneath mercury.

35 The apparatus of this invention and its details of construction may be more readily comprehended by reference to the accompanying more or less diagrammatic drawings, not to scale, in which:

40 Figure 1 is a vertical section of one form of the electrolytic cells of this invention.

Figure 2 is a vertical section of another form of our electrolytic cells in which the sealing means of the cell consists of a flexible seal attached to the side of the lid and the base of the cell.

45 Figure 3 is a vertical section of another specific embodiment of our cells.

Figure 4 is a vertical section of a cell in which the cover of the cell may be moved positively by applied force in both vertical directions.

Figure 5 is a vertical section of a cell having cover adjusting means comprising hydraulic rams for moving the cell cover positively in both directions and with the rod supporting the anode

supplied with means to prevent exudation of electrolyte from the end of the rod. Such means of preventing exudation of electrolyte are described and claimed in copending application Serial No. 695,624, filed September 9, 1946 by Arthur Wesley Ravenscroft, entitled "Electrode supports for electrolytic cells."

Figure 6 is a vertical section of another form of means for adjusting the vertical position of the cell cover and anode.

Figure 7 is a vertical section of still another form of a cell cover and anode adjusting means.

In these drawings like numbers represent like parts. Thus, in all these drawings 1 is the cell body which is a trough-shaped base having a plane bottom over which can flow mercury indicated at 2, while above the mercury aqueous electrolyte 3 can flow. The cells are provided with appropriate means (not shown) for supplying mercury and fresh electrolyte to the cell, for removing amalgam and spent electrolyte, for removing chlorine evolved in the electrolysis, and for supplying electric current to the electrodes. These appropriate inlets and outlets may take the customary form, and in the case of the forms of the invention shown in Figures 4 and 5 these inlets and outlets for the liquids will pass through the bottom of the cell to terminate as orifices within the area bounded by the peripheral channels.

Each cell has a lid or cover 4 carrying a number of solid carbon anode blocks 5 of known type (one of which is shown), each depending from a carbon rod 6 which passes through an opening in the lid, and through which current is supplied to the anode by means shown only in Figure 5. In the drawings the joint between the lid 4 and the rod 6 is sealed by a sealing composition 7, but any other suitable method of rendering the joint gas-tight may be employed. From each side of the lid 4 project a number of flanges 8 (one on each side being visible in the drawings), in which flanges in Figures 1 to 3 are threaded holes engaging with threaded bolts 9. In Figures 1 to 3 the bolts are shown to rest on lugs 10 projecting from the sides of the cell. This trough-shaped vessel 1 may be made of concrete or of steel, in the latter case being appropriately coated with ebonite or other material which will protect the steel against the corrosive action of the electrolyte and of the chlorine. The lid may also be made of concrete, slate, covered steel or the like.

Referring now more particularly to Figure 1, the sides of the cell body have around their upper edges a trough-shaped portion 11 in which is a layer of plastic, luting composition 12. When the cell is to be put into operation the anode blocks are fixed to the lid in the correct position to give more than the appropriate gap between the lower faces of anode blocks and the bottom of cell 1, and thus between those lower faces and the surface of the mercury 2 when the cell is in operation, and the lid is then put in position so that the bolts 9 rest on lugs 10. The exact height of the under-surface of the anode above the bottom of the trough is then determined, as by calculation from the predetermined dimensions of the trough of the anode-lid assembly and of the vertical distance between members 8 and 10. The inter-electrode gap is then adjusted accordingly by rotating bolts 9 so as to raise the heads of the bolts by a distance equal to that by which the anode has

to be lowered, and then pressing down the lid 4 until each bolt again rests on the corresponding lug 10. The cell is then ready for use. As the cell is used its resistance will gradually increase as the result of the wearing away of the under-surfaces of the anode blocks 5 and after a time the resistance will become uneconomically large. From a measurement of the increases in potential drop across the inter-electrode gap 10 and the known specific resistance of the electrolyte, it can be calculated by what amount it is necessary to lower the anode-lid assembly, and this is then effected while the cell is in operation by rotating bolts 9 so as to raise the heads of the bolts by that amount, and the lid is pressed down so that the bolts again touch the corresponding supporting member 10. The original efficiency of the cell will then be restored, but in time a further adjustment will be needed, and this can then be effected in similar fashion.

Referring now to Figure 2, in place of the member 11 and plastic composition 12 of Fig. 1 there is provided all around the cell where the gap 13 occurs between lid 4 and trough 1 an endless band 14 of a flexible material, having a resistance to chlorine, e. g., polyvinyl chloride, polythene, or chlorinated polythene, which is sealed to the walls of vessel 1. When the lid 4 has been lowered into its approximate position, as described in connection with Figure 1, this strip is also sealed in the same way to the periphery of lid 4. The fine adjustments to the position of the anode are then made as described in connection with Figure 1, except that the lid will sink under its own weight as the bolts 9 are raised, and in so doing will bend the flexible material 14. Adjustments during the running of the cell can also be made in the same manner.

Referring to Figure 3, the external adjusting means for adjusting the height of the anode is similar to that of the cell structure forms shown in Figures 1 and 2 consisting of bolts 9 which extend through the threaded flange 8 and rest upon the lugs extending from the cell body 1. The sealing means in this embodiment of the invention consists of a rigid skirt 17, integral with the lid 4 which extends downwardly into a channel 15 in the cell-body walls which is adapted to receive the skirt 17. In the base of the channel 15 is positioned a deformable resilient packing 16 such as an inflated rubber tube which is covered on both sides of the skirt by suitable material 17a, e. g., mercury, or an oil resistant to attack by chlorine.

In the form of the invention depicted in Figure 4, the vessel 1 is formed with a narrow deep channelled 15 extending the whole way around the plane surface on which mercury 2 flows. In the bottom of the channel 15 is an inflated rubber tube 16 and the lid 4 has a rigid skirt 17 integral with the lid and extending downwards far enough to dip into the channel 15 and to rest on the tube 16 when anodes 5 are in position.

In putting such a cell into operation the bottom of the vessel 1 is first flooded with mercury so as to fill channel 15, and thus cover the tube 16; the lid 4 is then caused to go into place by means of the bolts 9a in a position which gives approximately the correct inter-electrode gap. The bolts 9a are threaded into inserts 9b which are contained in the top of the sides of the housing 1. The skirt 17 will then rest on tube 16 and thus seal the space inside the cell from outside. Adjustments in the height of the anode can be

made as required by movement of the bolts 9a; if bolts 9a are lowered the positive downward thrust on the anode assembly will cause the skirt 17 to deform rubber tube 16 and thus allow the inter-electrode gap to decrease. If, initially, the inter-electrode gap is too small it can be increased by raising bolts 9a in the lugs 8, and the resilience of tube 16 ensures that the seal will still be maintained. Adjustments can be made in a similar manner during the use of the cell when the anode gap becomes too large as the result of wear.

In the embodiment shown in Figure 5, the cell is provided with a lid which is supported by a plurality of hydraulic rams disposed at intervals around the perimeter of the lid, the vertical adjustment of the lid being achieved by supplying or removing hydraulic pressure from the rams.

Depending from lid 4 is a skirt 17, the lower edge of which dips into the channel 15, and an endless inflated rubber tube 16a is disposed between the inner wall of the channel and the skirt. When the cell is in operation the channel will be filled with mercury, and the assembly of the skirt 17 and tube 16a will form a seal reinforced by the mercury; the rubber tube will thus be protected from the action of the electrolyte, which will contain dissolved chlorine, by the layer of mercury above it.

From each side of lid 4 project laterally a number of flanges 8 (one on each side being shown), each of which is attached to the upper end of a piston rod 18 of a hydraulic ram 19. Each ram is fitted with a pipe 20 above the upper limit of travel of the piston 21 and pipe 22 below the lower limit of travel of the piston. By means of appropriate two-way valves and an appropriate piping system, water under pressure can be supplied to the ram through each of the pipes 20 while water is allowed to leak away from below the pistons 21 through pipes 22, thus lowering the lid 4, and thus anode 5. On the other hand water can be supplied to the ram through all the pipes 22 and allowed to escape from pipes 20 thus raising the lid 4 and anodes 5.

Figures 6 and 7 illustrate modified forms of means external from the cell for adjusting the height of the anode of the cell relative to the liquid electrode. In Figure 6 there is shown a portion of the side of the cell body 1 provided with a lug 23. A wedge-shaped member 24 rides upon the lug 23 and is caused to move horizontally toward and away from the side of the cell by means of the bolt 25. A flange or lug 26 provided with a downwardly bent section which rests upon the upper face of the wedge 24 extends from the cover 4. The gap 13 between the cover 4 and the base 1 is sealed by means of the flexible seal 14 extending entirely around the outer periphery of the cover 4 and the top edge of the base 1. The base 1 in this case is made from iron and is provided with a lining 27 which may be made from any chlorine resistant material such as polyvinyl chloride, polythene, or chlorinated polythene.

In the embodiment shown in Figure 7, the base 1 is provided with a bracket 28 on which is journaled a cam 29. The flange 8 extending from the cover 4 rests upon the outer edge of the cam 29. The upper edge of the base 1 is provided with a trough 30 in which rests a portion of sealing composition 31 for sealing the gap between the cover 4 and the upper edge of the base 1. Adjustment of the height of the anode relative to the liquid cathode is obtained by rotating the

cam 29, the weight of the cover 4 and the remainder of the apparatus associated therewith being sufficient to cause the cover 4 to compress the sealing composition 31 and cause the cell to be sealed from the surrounding atmosphere.

Referring again in detail to Figure 5, there can be seen novel means for preventing exudation of electrolyte from the anode supporting rod which may be occasioned because of the cell being operated at super-atmospheric pressures. Thus, the upper end of the rod is threaded to receive a ring 32 of metal, ebonite, or other suitable material, which carries a stirrup 33 disposed immediately above the end of the rod, and a circular metal cap 34 rests with its rim on the upper surface of the ring screwed on to the rod; if desired a packing ring 35 of cork, rubber, or other compressible material may be interposed between the cap and the metal rim. The stirrup carries a set screw 36 adapted to bear against the top of the cap and to be rendered immovable by locknut 37. The space between the cap and the top of the anode is filled with a grease-like composition; this may be, for example, a grease-like mixture of a chlorinated naphthalene and a chlorinated paraffin wax, or a viscous chlorinated paraffin wax thickened by an addition of chlorinated rubber; a hydrocarbon grease could also be used.

In use, the set screw in the stirrup is made to press against the top of the cap, thus pressing the grease-like composition into the pores in the surface layers of the rod; as a result, electrolyte seeping up the pores of the rod will meet a barrier of grease-like material, and exudation of the electrolyte is prevented.

The ring and stirrup may be independent of the electrical connections to the rod, or they may, if desired, be part of such connections. Thus the ring and stirrup may be of copper, and the electrical leads 38 to the rod may be clamped to the stirrup by the locknuts for the set screw.

Operation of the cells which use a sealing composition interposed in a trough-like unit on the top edge of the sides of the base, e. g., forms of apparatus such as shown in Figures 1 and 7, is commenced by setting the lid slightly above the highest position it will need to occupy by moving the screw-adjusting means; the gap between the lid and the top of the cell is then closed by packing in a plastic luting composition. If the inter-electrode gap is found to be too large the screw-adjusting means can be actuated to allow the gap to be reduced by the appropriate amount. If the screw-adjusting means provides positive movement of the lid towards the vessel the plastic composition will thus automatically be deformed and the solid electrodes brought to the correct position. However, if the screw-adjusting means gives positive movement of the lid only in the one direction, (upwards), the necessary adjustment can be made by screwing the bolts in the appropriate direction by the amount by which it is desired to lower the electrodes, whereupon, if the sealing composition is sufficiently plastic, the lid will sink by its own weight until the bolts are again resting on the ledge. If the composition is too stiff for this purpose, the lid can then be pressed down by hand pressure or otherwise until the result is achieved. The amount by which the lid is lowered may be chosen in accordance with the known rate of wear of the electrodes (under given operating conditions) or by other methods; for example, it may be chosen so that the cell voltage is kept between specified limits.

When the electrodes require renewal the lid is removed, the electrodes fixed in position, the lid replaced and the sealing composition renewed, preferably after making at least the preliminary adjustments in the height of the lid by means of the bolts.

In the forms of the invention using the integral skirt on the cell lid combined with a seal of resilient packing and mercury or other sealing liquid such as oil, the rubber tube should not be inflated so hard that it cannot be deformed, but nevertheless sufficient for it to be resilient. On supplying mercury to the cell the space in the channel above the rubber tube is filled with mercury and the rubber is thus prevented from coming into contact with gaseous chlorine, or with brine containing dissolved chlorine, thereby deteriorating and losing its resilience. By providing the resilient deformable packing in the channel the diversion of the mercury flow from the plane surface to the channel can be reduced to small proportions. It will be apparent that this latter desirable condition can more readily be realized if the thickness of the sides of the cover is only slightly less than the width of the channel. In making an adjustment to the position of the lid, it is merely necessary to reset the position of the nuts on which the lugs of the lid rest, and the weight of the latter will cause the rubber packing in the channel to be deformed as the lid is lowered. If desired, the adjustment may thus be made without breaking the seal and may even be made without interrupting the electrolysis. To guard against the generation of sufficient pressure inside the cell to cause the lid to press upwards instead of downwards, threaded rods may be secured to the sides of the cell trough, which rods pass through holes in the lugs of the lid, two nuts being then provided on each rod, one above the lug and one below it. The seal will then not be broken even if the lid is pressed upwards through the pressure of chlorine in the cell.

In any of the above forms of the invention, various luting compositions may be used which are relatively inert to chlorine, for example, a plastic mixture of chlorinated paraffin wax, chlorinated polythene, neoprene and the like. However, the invention is not limited to the use of plastic compositions, but also includes the use of liquid seals, e. g., brine, or of mercury covered with a layer of a hydrocarbon oil to prevent attack within the cell by chlorine. As indicated, we may also make the seal by means of a strip of rubber or other flexible impermeable material extending over the short gap between the lid and the wall and sealed to each by tar, pitch or other luting composition. In those forms of the invention in which the cell lid is provided with a skirt which suspends into a channel in the cell body, it has been found that usually fine operational results are obtained where the channel is filled with a thermoplastic substance inert to the gases evolved in the electrolysis and capable of wetting the surfaces of the skirt and channel in lieu of the mercury and deformable tubing seal described above. Electrolytic cells of the liquid electrode type incorporating a thermoplastic seal of this kind are described and claimed in copending application, Serial No. 695,625, filed Sept. 9, 1946 by Arthur Wesley Ravenscroft entitled "Electrolytic Cells" now Patent Number 2,502,888. Suitable thermoplastic materials which may be used include normally solid chlorinated naphthalene containing, for example, 45 to 55% chlorine, solid chlorin-

ated paraffin wax, mixture of chlorinated naphthalene and chlorinated wax, and the like.

As many and varied modifications of the subject matter of this invention will become apparent to those skilled in the art from the detailed description given hereinbefore, it is to be understood that this invention is to be limited only in accordance with the appended claims.

We claim:

1. An electrolytic cell of the liquid electrode type having a base carrying a flowing liquid electrode, a cover on the base extending across the cell beyond the edges of the liquid electrode, a solid electrode rigidly supported in the cell by said cover, said solid electrode having a plane under-surface disposed a short distance above the upper surface of the liquid electrode and substantially parallel thereto, said plane surface extending continuously across the major portion of the cell, means combined with the cover for adjusting the height of the cover relative to the base comprising a plurality of horizontal extensions on said cover which bear upon vertically adjustable support members carried by said base, and means for sealing the cover to the base for allowing appreciable relative vertical movement between the cover and the base comprising an elongated, resilient element of a length corresponding to the perimeter of said base in sealing engagement with the peripheral edges of said cover and said base.
2. In an electrolytic cell of the liquid electrode type having a base carrying a flowing liquid electrode, a cover on the base extending across the cell beyond the edges of the liquid electrode and a solid electrode having a plane under-surface rigidly supported in the cell by said cover with its undersurface disposed a short distance above the upper surface of the liquid electrode and substantially parallel thereto, said solid electrode extending continuously across the major portion of the cell, the combination which comprises means combined with the cover for adjusting the height of the cover relative to the base comprising a plurality of horizontal extensions on said cover which bear upon vertically adjustable support members carried by said base, upwardly extending walls integral with the base, and means for sealing the cell comprising a layer of plastic composition filling a gap between the lower side of the cover and the top edges of the walls of the base.
3. In an electrolytic cell of the liquid electrode type having a base carrying a flowing liquid electrode, a cover on the base extending across the cell beyond the edges of the liquid electrode and a solid electrode having a plane under-surface rigidly supported in the cell by said cover with its under-surface disposed a short distance above the upper surface of the liquid electrode and substantially parallel thereto, said solid electrode extending continuously across the major portion of the cell, the combination which comprises means combined with the cover for adjusting the height of the cover relative to the base comprising a plurality of horizontal extensions on said cover which bear upon vertically adjustable support members carried by said base, and means for sealing the cell which comprises an endless band of chlorine impervious flexible material surrounding a gap between the cover and the base, the opposite edges of said band being sealed to the cover and base, respectively.
4. In an electrolytic cell of the liquid electrode type having a base carrying a flowing liquid elec-

trode, a cover on the base extending across the cell beyond the edges of the liquid electrode and a solid electrode having a plane under-surface rigidly supported in the cell by said cover with its under-surface disposed a short distance above the upper surface of the liquid electrode and substantially parallel thereto, said solid electrode extending continuously across the major portion of the cell, the combination which comprises means combined with the cover for adjusting the height of the cover relative to the base comprising a plurality of horizontal extensions on said cover which bear upon vertically adjustable support members carried by said base, a peripheral channel in said base, a skirt integral with said cover depending into said channel, a deformable, resilient packing within said channel contacting a wall of the channel and of the skirt, said packing being covered by a layer of sealing liquid contained in the channel.

5. In an electrolytic cell of the liquid electrode type having a base carrying a flowing liquid electrode, a cover on the base extending across the cell beyond the edges of the liquid electrode and a solid electrode having a plane under-surface rigidly supported in the cell by said cover with its under-surface disposed a short distance above the upper surface of the liquid electrode and substantially parallel thereto, said solid electrode extending continuously across the major portion of the cell, the combination which comprises means combined with the cover for adjusting the height of the cover relative to the base comprising a plurality of threaded bolts operatively engaging the cover and bearing against a portion of the base, and means for sealing the cover to the base in a manner allowing relative vertical movement between the cover and the base comprising an elongated, resilient element of a length corresponding to the perimeter of said base in sealing engagement with the peripheral edges of said cover and said base.

6. In an electrolytic cell of the liquid electrode type having a base carrying a flowing liquid electrode, a cover on the base extending across the cell beyond the edges of the liquid electrode and a solid electrode having a plane under-surface rigidly supported in the cell by said cover with its under-surface disposed a short distance above the upper surface of the liquid electrode and substantially parallel thereto, said solid electrode extending continuously across the major portion of the cell, the combination which comprises means combined with the cover for adjusting the height of the cover relative to the base comprising a plurality of threaded bolts operatively engaging the cover and the base, and means for sealing the cover to the base in a manner allowing relative movement between the base and cover comprising a peripheral channel in the base, a skirt integral with the cover depending into the channel, a deformable resilient packing within said channel contacting a face of the skirt and the channel wall, said packing being covered by a layer of sealing liquid contained in the channel.

7. An electrolytic cell of the liquid electrode type, which may be operated at an appreciable internal pressure and in which the inter-electrode gap may be adjusted without interruption of the cell operation, having a base carrying a flowing mercury electrode, a cover which extends substantially over the cell, a solid electrode

rigidly supported in the cell by said cover, said solid electrode having a plane under-surface disposed a short distance above the upper surface of the liquid electrode and substantially parallel thereto, said plane surface extending continuously across the major portion of the cell, means combined with the cover for adjusting the height of the cover relative to the base comprising a plurality of horizontal extensions on said cover which bear upon vertically adjustable support members carried by said base, and means for sealing the cover to the base for allowing sufficient relative vertical movement between the cover and the base to substantially alter the width of the inter-electrode space by such relative movement comprising an elongated, resilient element of a length corresponding to the perimeter of said base in sealing engagement with the peripheral edge portions of said cover and said base.

8. An electrolytic cell of the mercury electrode type capable of being operated with a substantial fluid pressure differential between its electrolyte inlet and outlet, which comprises a base carrying a flowing mercury cathode, a cover on the base extending across the cell beyond the edges of said cathode, a solid electrode with a plane under-surface of such width as to extend nearly across the cell, said electrode being rigidly supported in the cell by said cover so that vertical movements of the cover cause equal vertical movements in the electrode with its under-surface disposed a short distance above the upper surface of the liquid electrode and substantially parallel thereto, means combined with the cover for adjusting the height of the cover relative to the base, comprising a plurality of horizontal extensions on said cover which bear upon vertically adjustable support members carried by said base, and means for sealing the cover to the base for allowing sufficient relative vertical movement between the cover and the base to substantially alter the width of the inter-electrode space by such relative movement, comprising an elongated, resilient element of a length corresponding to the perimeter of said base in sealing engagement with the peripheral edge portions of said cover and said base.

9. An electrolytic cell as claimed in claim 1, wherein said means combined with the cover for adjusting the height of the cover relative to the base comprises a plurality of threaded bolts operatively engaging the cover and engaging threaded holes in said base.
